Application April 24, 1956, Serial No. 41,194

Term of patent 14 years

(Cl. D34—15)

FIG. 1

FIG. 2

FIG. 3

FIG. 4

FIG. 5

Fig. 1 is a side view of a toy whistle ring showing my new design;

Fig. 2 is a front view thereof;

Fig. 3 is a rear view thereof;

Fig. 4 is a top view thereof; and

Fig. 5 is a bottom view thereof.

The characteristic features reside in the beveled upper and lower surfaces of the whistle element in relation to and in association with all of the other parts, as shown.

I claim:

The ornamental design for a toy whistle ring, substantially as shown and described.
